UNITED STATES PATENT OFFICE.

CHARLES H. READ, OF PITTSBURG, PENNSYLVANIA.

DESIGN FOR A POCKET-FLASK.

SPECIFICATION forming part of Design No. 19,230, dated July 23, 1889.

Application filed June 22, 1889. Serial No. 315,277. Term of patent 3½ years.

To all whom it may concern:

Be it known that I, CHARLES H. READ, a citizen of the United States, residing at Pittsburgh, in the county of Allegheny and State 5 of Pennsylvania, have invented and produced a new and original Design for Pocket-Flasks; and I do hereby declare the following to be a full, clear, and exact description of the same, reference being had to the accompanying drawings, forming a part thereof.

The leading feature of my design consists in the flask representing a boxing-glove, one 15 side of the flask being oval to conform to the shape of the back of a boxing-glove, the other or front side of the flask being slightly concaved to represent the palm of the hand, and around which, in their natural order, are arranged the thumb and the four fingers of 20 the hand, formed in indented outlines, as shown in Fig. 1.

A indicates the main body of the flask; B, the thumb, and C the fingers.

D is a band formed on the upper end of 25 the flask, and is of an oval shape to correspond to the human wrist.

E is a central projection formed centrally of the flask, and is provided with a cap or cover F, which is spirally fluted, as shown. 30

What I claim is—

The design for a flask, as herein shown and described, the same consisting of the oval back, the concaved front, having indented outlines of the thumb and fingers of the human hand, provided with a neck or band D and a spirally-fluted top or cover F, as set forth, representing a boxing-glove. 35

In testimony whereof I affix my signature in presence of two witnesses.

CHARLES H. READ.
